UNITED STATES PATENT OFFICE.

PETER J. FAGAN, OF WEST HOMESTEAD, PENNSYLVANIA.

TRUSS.

Application filed November 28, 1922. Serial No. 603,814.

To all whom it may concern:

Be it known that I, PETER J. FAGAN, a citizen of the United States, residing at West Homestead, in the county of Allegheny and State of Pennsylvania, have invented certain new and useful Improvements in Trusses, of which the following is a specification.

This invention relates to an improvement in trusses, and more particularly to an improvement in the construction of the pads of surgical appliances of this type.

One of the primary objects of the invention is to so construct the pad that it will exert pressure against the rupture in a manner to insure against protrusion and at the same time cause minimum inconvenience to the wearer.

Another object of the invention is to so construct the pad that its position with relation to the band of the truss may be varied or adjusted to suit the comfort of the wearer, and the invention contemplates such an arrangement of parts as will insure against disarrangement after the desired adjustment has been effected.

Another object of the invention is to provide a truss pad embodying a pressure element designed to bear with a desirable degree of firmness against or into the rupture, and a cushioning medium surrounding said element to bear with a lesser degree of firmness against the abdominal wall about the rupture, and in this connection the invention contemplates a relative adjustment of the parts so that the pressure element may be projected a greater or less distance beyond the surface of the surrounding cushioning medium.

40 In the accompanying drawings:

Figure 1 is a perspective view of the truss embodying the invention;

Figure 2 is a vertical sectional view through the pad of the truss and the portion of the band by which it is supported;

Figure 3 is a group perspective view illustrating several component parts of the pad disassembled and removed from the body band of the truss.

50 In the drawings the body band or strap of the truss is indicated in general by the numeral 1 and preferably comprises, as usual, an open metallic band 2 having a covering or sheathing 3 of leather, the band 55 being appropriately shaped to fit snugly about the body in the usual manner. The

pad embodying the invention is adaptable for application to body bands of various forms and constructions but to provide for the support of the pad it is desirable that the band 2 be formed with a longitudinally extending slot 4.

The pad structure is indicated in general by the numeral 5 and the same consists in part of a base comprising a pair of circular disc-like members indicated one by the numeral 6 and the other by the numeral 7. The member 6 is provided centrally with an opening 8 and upon one face with a lug 9 through which the opening also extends, this lug being preferably flattened upon opposite sides as indicated by the numeral 10 so as to adapt it to fit slidably in the slot 4 with its flattened side contacting the upper and lower walls of the slot. In this manner the member 6 of the base is supported upon the band 2 for adjustment in the direction of the length of the band but is securely held against rotation. The member 7 of the base is disposed against the inwardly presented face or side of the member 6 in peripheral registration with the said member and is formed centrally with a threaded socket 11 into which is fitted the end of a screw 12 which screw is likewise fitted through the opening 8. The screw 12 when loosened, constitutes a pivot about which the member 7 may be rotated for a purpose to be presently explained, and when tightened serves to draw the member 7 firmly against the member 6 and likewise bind the member 6 against the inner side of the band of the truss so as to secure the pad structure in place upon the band, it being understood that upon loosening of the screws the base comprising the members 6 and 7 may be adjusted in the direction of the length of the band within the limits of the movement of the lug 9 in the slot 4 and that after the base has been suitably positioned, the screw may be tightened to bind the parts in place.

105 In order that the member 7 may be held in various positions of its rotative adjustment, its face which contacts the face of the member 6, is formed with an annular series of sockets 13 concentric to the axis of the said member, and the member 6 is provided with a stud 14 which is designed to seat in the sockets 13 interchangeably. At this point 110 it will be evident that by loosening the screw 12 without, however, completely unthread-

ing it from the socket 11 in the member 7, the member 7 may be displaced with relation to the member 6 a sufficient distance to clear the stud 14 whereupon the said member 7 may be rotatably adjusted to the desired position and then again brought into facial contact with the stud 14 engaging in that one of the sockets 13 which is at such time opposite the stud, and the screw 12 may then be tightened to secure the parts against future separation or displacement until the said screw is again loosened.

The pressure exerting element of the pad structure comprises a finger which is indicated in general by the numeral 15 and which is preferably in the nature of a cylindrical post securely anchored at one end to the inwardly presented face of the member 7 preferably near the periphery thereof and therefore eccentric to the axis of the said member 7. The post is rounded at its engaging end as indicated by the numeral 16 so as not to irritate the flesh where it is brought into engagement therewith, and the said post is threaded from a point adjacent its said end to a point adjacent its inner end, as indicated by the numeral 17. The cushion of the pad is indicated in general by the numeral 18 and the same comprises a flat circular backing member 19 having a threaded opening 20 formed centrally therein and receiving the finger 15, the threaded engagement of these parts permitting of adjustment of the member 19 longitudinally of the finger upon rotation of the said member 19. If desired the periphery of the member 19 may be milled as at 21 to permit of more convenient rotation thereof to adjust the same. A cushioning body 22 of sponge rubber, or any other soft material suitable for the purpose, is supported upon the inwardly presented face of the backing member 19 and is rounded or otherwise molded or formed to best adapt it to bear firmly against the wall of the abdomen about the rupture with minimum inconvenience to the wearer of the truss. By reference to Figure 2 of the drawings it will be observed that the rounded engaging end 50 of the finger 15 protrudes beyond the bearing surface of the cushion 22 and it will be evident that by rotating the backing member 19, the member, together with the cushion, may be adjusted longitudinally of the finger so as to vary the distance to which the said end of the finger protrudes beyond the surface of the said cushion.

From the foregoing description of the invention it will be seen that the pad structure as a whole may be adjusted in the direction of the body band of the truss; the base member 7 may be rotatably adjusted so as to suitably position the finger 15 and the associated cushion 22; and, the cushion 65 may be adjusted with relation to the finger

so that a greater or less length of the finger may project beyond the cushion.

Having thus described the invention, what is claimed as new is:

1. In a truss, a body band, a base member supported thereon, a second base member associated with the first-mentioned member and having a threaded socket, a pivot screw rotatably fitted through the first-mentioned base member and adjustably threaded into the socket in the second-mentioned member, one of said members being provided in its contacting face with a series of sockets concentric to its axis and the other member being provided with a stud upon its corresponding face for engagement in the sockets interchangeably, and a pressure element supported upon the second-mentioned base member eccentric to the axis of rotative adjustment thereof. 70

2. In a truss, a body band having a longitudinal slot, a base member disposed against the inner side of the band and having a lug upon its face engaging in the slot, the said member and its lug being formed with an opening, a second base member disposed against the first-mentioned member and having a threaded socket, a screw fitted through the slot in the band and through the opening in the first-mentioned base member and its lug and adjustably threaded into the socket in the second-mentioned base member, one of said base members having a series of sockets concentric to its axis, a stud upon the other base member engageable in the sockets interchangeably in the rotative adjustment of the second-mentioned base member about the said screw as an axis, and a pressure element supported upon the second-mentioned base member eccentric to the axis of rotative adjustment thereof. 90

3. In a truss, a body band, a base member disposed against the inner side of the band and comprising a circular disc, a second base member comprising a circular disc disposed against the inwardly presented face of the first mentioned disc in peripheral registration therewith, means axially pivotally connecting the said disc whereby the second mentioned disc may have rotative 110 adjustment with relation to the first mentioned disc, the said means likewise securing the said base members to the said body band, coating means upon the contacting faces of the discs for holding the second mentioned disc in positions of adjustment with relation to the first mentioned disc, a stud supported upon the second mentioned disc eccentric to the axis thereof, and a pressure element supported upon the said stud. 120

In testimony whereof I affix my signature.
